UNITED STATES PATENT OFFICE.

EUGENE S. CARLSEN, OF CHICAGO, ILLINOIS.

HAIR-CLIPPER.

1,355,309.

Specification of Letters Patent. Patented Oct. 12, 1920.

Application filed May 20, 1920. Serial No. 382,780.

To all whom it may concern:

Be it known that I, EUGENE S. CARLSEN, a citizen of the United States, residing at Chicago, in the county of Cook and State of Illinois, have invented certain new and useful Improvements in Hair - Clippers, of which the following is a specification.

This invention relates to improvements in an individual or adjustable hair clipping or cutting device, or in other words, to improvements in that type of hair clippers or cutters which are more particularly intended for use by a person in the operation of cutting or clipping his own hair.

The invention has for its main object to furnish a hair clipper or cutter device which shall be simple and inexpensive in construction, strong, durable and efficient in operation, with its parts so made, arranged and coöperating with one another as to enable the cutting members or knives to be adjusted or turned to either side of the handles thereof, and there fixed in the proper position, to the end, that the instrument can be used by either hand of the individual in cutting his own hair, and in such a way that the rounded or smooth surface of the supporting body of the device will be presented to the head in the operation thereof.

Other objects and advantages of the invention will be set forth in the following description and explanation.

The invention consists in certain peculiarities of the construction, novel arrangement and operation of the various parts thereof as will be hereinafter more fully set forth and specifically claimed.

In the accompanying drawing, which serves to illustrate an embodiment of the invention—

Figure 1 is a plan view of the device with its parts in their normal positions when used by the left hand of the operator in cutting his hair on the left hand side of his head.

Fig. 2 is an edge view thereof looking toward the cutting edge of the instrument.

Fig. 3 is a cross-sectional view taken on line 3—3 of Fig. 1 looking in the direction indicated by the arrows.

Fig. 4 is a view looking at the front end of the device when the parts are positioned as shown in Fig. 1, and

Fig. 5 is a plan sectional view taken on line 5—5 of Fig. 3 as indicated by the arrows.

Like numerals of reference refer to cor-

responding parts throughout the different views of the drawing.

The reference numeral 7 designates the base or body carrying handle of the clipper, 60 which is slightly curved from the other handle 8 thereof and is provided on its outwardly bowed portion at about the middle thereof with a thumb-guard 9 which is forked as shown in Figs. 1, 2 and 4 of the 65 drawing for the purpose of receiving between said forks or prongs the thumb of the hand in which the instrument is held when being used. The other handle 8 is provided on its outer portion with a projection 10 to 70 assist in gripping the handle members, for it will be understood that the fingers will grasp the handle 8 while the thumb engages the guard 9 on the outer surface of the first named handle.

The handle 7 is provided at its front portion with a lateral extension 11 which is located rearwardly of the front end of said handle as is shown in Fig. 1 and is provided transversely with an opening through 80 which is extended a plunger or rod 12 which has mounted on its rear end, preferably by being screwed thereon, a head 13 which is provided in its rear end with a pair of spaced apart projections 14 between which 85 is located a cam extension 15 extended from the front end of the handle 8, which handle is pivotally connected to the handle 7 by a pivot 16 near the rear end of the supporting body 17 as is clearly shown in Figs. 1 and 2 90 of the drawing.

The front end of the plunger or rod 12 is provided with a pair of prongs 18 between which is located a stud 19 extended at a right angle from a member or plate 20 95 which is pivotally mounted on the cylindrical portion 21 of a projection 22 extended from the base 23 of a segmental plate 24 which is provided with an arcuate slot 25 through which is extended a set-screw 26 100 which engages a suitable opening in the handle member 7 near the extension 11 thereon but in its opposite surface.

The forward extension 27 of the handle member 7, or that portion of said member in 105 front of the lateral extension 11 is pivotally secured to the plate 24 by means of a screw or suitable pivot 28, see Fig. 3, just above the base 23 of said plate, and the front end of the extension 27 is by preference rounded 110 or of such length forwardly of the pivot 28 to permit of the relative rotary movements

of the handle members and the supporting body 17 in order that the parts may be changed from the positions shown by continuous lines in Fig. 2 of the drawing to that shown by dotted lines in said figure, which change of positions will adapt the device to be used in the right hand of the operator in clipping or cutting the hair on the right hand side of his head. The stud 19, 10 which as before stated is extended between the prongs 18 of the plunger rod 12 is provided near its free end with a transverse opening 29 which as shown in Fig. 3 is flared at each of its ends to permit of a 15 slight lateral movement of the prongs 18 of the plunger or rod 12, which prongs are secured to the stud 19 by means of a pin 30 extended transversely thereof and through the opening 29 in said stud. That end of 20 the member 20 opposite the stud 19 thereon is provided with an extension 31 which engages a recess 32 in the inner edge of the reciprocating cutter-bar 33, which bar is slidably mounted on the flat and inner surface of the supporting body 17, which body has its outer surface rounded cross-sectionally as shown in Figs. 3 and 4 of the drawing. The bar 33 is provided at its outer edge with spaced knives or cutters 34 which 25 co-act with similar knives or cutters 35 on the corresponding edge of the body 17. This latter bar is provided with a longitudinal slot 36, see Fig. 5, through which extend studs 37 mounted on the supporting body 30 37 and extended from the flat or inner surface thereof. By this arrangement it is apparent that the reciprocating bar 33 will be guided by means of the slot 36 and the pins or studs 37 for back and forth movement on 35 the supporting body.

In order to hold the reciprocating cutter-bar 33 in position on the body 17 the latter is provided at a point about the longitudinal middle thereof with an opening 38 which 40 registers with the slot 36 and is for the reception of a screw 39 which extends through the slot 36 and through a suitable opening in a keeper-bar 40 which is longitudinally channeled to receive a correspondingly extended rib on the upper surface of the bar 33, which construction will further provide a guiding means for the back and forth movement of the reciprocating cutter-bar. The keeper-bar 40 is provided with a pair 45 of openings 41 to receive the studs 37 and thus prevent any movement of said bar.

Mounted on the inner or upper end of the screw 39 is a milled nut 42 by means of which the keeper-bar is held in position.

60 Located between the extension 11 on the handle member 7 and the head 13 on the plunger or rod 12 and surrounding the same is a spring 43 which has one of its end in engagement with the extension 11 and the other in engagement with the head 13, and

is employed for retracting the handle members after they have been pressed toward each other in the operation of the device.

From the foregoing and by reference to the drawing it will be understood and clearly seen, that assuming the parts to be in their normal positions as shown in the different views of the drawing and with the cutting members located as shown, the device is ready for use in the left hand of the operator by simply placing the thumb of said hand outwardly of the member 7 and between the prongs 9 of the thumb guard and by placing the fingers of said hand outwardly of the handle 8 and astride the projection 10 thereon when it is obvious that the rounded surface of the supporting body 17 can be placed against the neck or head of the user with the cutters or knives extended upwardly, when by intermittently gripping and releasing the handle members 7 and 8 the reciprocating cutter-bar 33 will, through said gripping action and the instrumentality of the spring 43, be moved back and forth on the supporting body 17 in such a way as to cause the cutters 34 of the reciprocating bar to co-act with the cutters 35 in clipping or cutting the hair interposed between the same.

Now, when it is desired to adjust the body 95 with respect to the handle members, for use in the right hand of the operator, all that is necessary is to loosen the set-screw 26 and turn the supporting body 17 from the position shown by continuous lines to that 100 shown by dotted lines in Fig. 2 of the drawing when it is obvious that the cutting members on the supporting bar will be presented upwardly but at the opposite sides of the handle members. As it may be desirable, 105 sometimes to set the cutting members at an angle to the handle members, instead of in parallelism therewith as shown, the face of the plate adjacent the head of the screw 26 may be provided at its periphery with guide- 110 marks 44 which will indicate to about what angles the supporting body may be turned without interfering with the operation of the device.

Having thus fully described my invention, 115 what I claim as new and desire to secure by Letters Patent is:

1. In a hair clipper, the combination with a handle member having a lateral extension near its front end, of a plate mounted on the front portion of said member for rotation in a plane parallel therewith and having an arcuate slot, a cutter carrying supporting body rigidly mounted on said plate at right angles thereto, a cutter carrying bar 120 slidably mounted on said supporting body, a member pivotally mounted between said plate and body and engaging said cutter carrying bar, another handle member pivoted to the first named handle member and hav- 130

ing an extension at its front end, a spring-
actuated plunger slidably mounted on said
lateral extension and operatively engaging
at its rear end the extension of the last
5 named handle member, means loosely con-
necting the front portion of the plunger
with said pivoted member, and a set-screw
extended through the arcuate slot and en-
gaging the front portion of the first named
10 handle member.

2. In a hair clipper, the combination with
a handle member having a lateral extension
near its front end, of a plate mounted on the
front portion of said member for rotation
15 in a plane parallel therewith, a cutter car-
rying supporting body rigidly mounted on
said plate at right angles thereto, a cutter
carrying bar slidably mounted on said sup-
porting body, a member pivotally mounted
20 between said plate and body and engaging
said cutter carrying bar, another handle
member pivoted to the first named handle
member and having an extension at its front
end, a spring-actuated plunger slidably
25 mounted on said lateral extension and oper-
atively engaging at its rear end the exten-
sion of the last named handle member, and
means loosely connecting the front portion
of the plunger with said pivoted member.

3. In a hair clipper, the combination with 30
a handle member having near its front end
a lateral extension provided with an opening
and said member having forwardly of said
lateral extension a longitudinal extension
provided with a transverse opening, of an- 35
other handle member pivoted to the first
named member and having at its front end
a cam extension, a spring-actuated plunger
movably located in the opening of said lat-
eral extension and operatively engaging at 40
its rear portion said cam extension, a plate
rotatably mounted on the longitudinal ex-
tension and having an arcuate slot near its
periphery and provided with a base at an
angle thereto, said base having a projection 45
opposed to the plate, a supporting body fixed
on said projection and having knives or cut-
ters at one of its side edges, a reciprocatory
cutter carrying bar mounted on the said
body and having a recess in one of its edges, 50
a member pivotally mounted on said projec-
tion and having an extension engaging said
recess, said member having a stud in loose
connection with the front portion of said
plunger, and a set-screw extended through 55
the slot of the rotatable plate and engaging
the first named handle member.
